Patented Apr. 6, 1915.

UNITED STATES PATENT OFFICE.

ALBERT C. RIGHTOR, OF PITTSBURGH, PENNSYLVANIA.

SAFETY-HEEL.

1,134,228.

Specification of Letters Patent.

Patented Apr. 6, 1915.

Application filed April 10, 1914. Serial No. 830,962.

To all whom it may concern:

Be it known that I, ALBERT C. RIGHTOR, a citizen of the United States, residing at Pittsburgh, in the county of Allegheny and State of Pennsylvania, have invented or discovered certain new and useful Improvements in Safety-Heels, of which the following is a specification, reference being had therein to the accompanying drawings.

10 This invention relates to antislapping devices for boots and shoes, particularly those capable of being thrown into and out of operative position to engage the surface walked upon at the will of the user, and has 15 for its objects to provide a simple, inexpensive, practical, efficient and convenient device of this character, one which is well adapted for use in connection with rubber and other resilient heels, and one which may 20 be readily applied to an existing boot or shoe without other modification of the heel thereof than the removal of the usual number of lifts incidental to the application of a rubber heel or lift of ordinary form. 25 The foregoing and other objects of the invention, together with means whereby the same may be carried into effect, will best be understood from the following description of one form or embodiment thereof illustrated in the accompanying drawings. It 30 will be understood, however, that the particular construction described and shown has been chosen for illustrative purposes merely, and that the invention, as defined by the 35 claims hereunto appended, may be otherwise embodied and practised without departing from the spirit and scope thereof.

In said drawings: Figure 1 is a longitudinal vertical section of a safety heel or 40 auxiliary lift and associated devices constructed in accordance with the invention, a portion of the regular heel lifts and other parts of the shoe being shown in side elevation. Fig. 2 is a bottom plan view partly 45 broken away. Fig. 3 is a section on the line 3—3, Fig. 1, showing the antislapping device in retracted or inoperative position. Fig. 4 is a similar view showing the anti- 50 slipping device in projected or operative position. Fig. 5 is a top plan view of the auxiliary lift. Fig. 6 is a perspective view of the plate associated with the auxiliary lift and carrying the operating means for the antislapping device.

55 The complete device constituting the present invention comprises an auxiliary heel or

outer lift 12, preferably of rubber or other suitable resilient material, and certain associated parts, said complete device being adapted for application to the regular heel 60 13 of an ordinary boot or shoe in substitution for one or more of the outer lifts of said regular heel in a manner similar to the application of the well-known rubber heels or lifts now in extensive use. Associated 65 with the auxiliary lift and interposed between the same and the heel 13 is a plate 14, preferably of metal. The plate 14 is provided on its under side with transversely arranged guide flanges 30 for a purpose presently to be explained. The flanges 30 are 70 preferably formed integral with the plate 14, being struck up from the body of said plate, thereby leaving openings 17. The auxiliary heel or lift 12, together with the 75 plate 14, is secured to the heel 13, after the removal of the necessary number of lifts, by means of nails 16 which pass through the openings 17 in the plate 14 and nails 18 which pass through other suitably disposed 80 openings 19 in the plate 14, said nails 16 and 18 entering the heel 13. The auxiliary lift 12, when composed of rubber or the like, preferably has embedded therein at suitable point washers 20 through which the nails 85 18 pass, said washers engaging the heads of said nails and preventing said heads from pulling through the rubber lift 12.

The creeper, calk, or antislapping device 90 21 preferably comprises a block or plate 95 having a roughened outer surface or edge and is arranged for vertical movement in a slot 22 extending through the auxiliary lift 12 and arranged transversely thereof. When said auxiliary lift is composed of rubber or 95 the like there is preferably embedded therein a plate 23 having a central opening to receive the calk or antislapping device 21, thereby guiding said antislapping device for vertical movement and preventing lateral 100 displacement thereof. The plate 23 is preferably formed with suitably disposed openings through which the nails 16 pass, thereby not only securing said plate directly to the heel 13 but also preventing the heads 105 of said nails from pulling through the rubber lift 12. The antislapping device 21 is moved upwardly into its inoperative position within the heel by means of a leaf spring 24 secured at one end to the under 110 surface of the plate 14 adjacent the rear end thereof and engaging at its free for-

ward end a slot 25 in the antislipping device 21. Said spring 24 is received in a recess 26 formed in the upper surface of the auxiliary lift 12 and extending rearwardly from the 5 slot 22. The means for projecting the anti-slipping device 21 downwardly into its operative position against the tension of the spring 24, and for retaining said device in said position, comprises a cam slide or plate 27 having a lower cam surface 28 engaging and co-operating with an upper cam surface 29 on the anti-slipping device 21. The cam slide or plate 27 is guided for lateral movement in the slot 22 between the flanges 30 10 on the plate 14 which extend into the slot 22, said slot being formed with a flared upper end to receive said flanges. The cam plate 27 is operated to project or release the anti-slipping device 21 by means of a lever 31 15 pivoted adjacent its center, as at 32, to the plate 14 and at its rear end on a pin or stud 33 projecting upwardly from the cam plate 27 within a recess 34 in the upper face of said cam plate into which the end of said 20 lever extends. The lever 31 is received in a recess 35 in the upper face of the auxiliary lift 12, said recess extending forwardly from the slot 22 to the breast of the heel beyond which the forward or operating end 25 of the lever 31 projects.

The normal or inoperative position of the parts is as shown in Figs. 2, 3 and 6 and in full lines in Fig. 1, in which position the anti-slipping device 21, under the influence 30 of the spring 24, is lifted into a position entirely within the lift 12 and above the lower surface thereof, so as to be out of engagement with the surface walked upon. At this time the position of the cam plate 27 is 35 such as to permit such lifting of the anti-slipping device 21 by its spring 26, *i. e.*, the high portions of the cam surface 28 are opposite low portions of the cam surface 29, and vice versa. In order to project the anti-slipping device into operative position, as 40 shown in Fig. 4 and in dotted lines in Fig. 1, for use on slippery surfaces, the forward end of the lever 31, which is extended to a convenient point in front of the breast of the 45 heel and beneath the instep, is moved transversely of the heel, thereby swinging said lever on its pivot 32, and moving the cam plate 27 from the position shown in Fig. 3 into that shown in Fig. 4. During this 50 movement of the cam plate 27 engagement of the cam surface 28 with the cam surface 29 causes the anti-slipping device 21 to be projected downwardly into operative position against the tension of the spring 24. The 55 cam surfaces 28 and 29 are so formed that, when the cam plate 27 is moved into the extreme position shown in Fig. 4, interengagement of high portions of said surfaces will cause said anti-slipping device to be positively locked in its operative position, up-

ward thrust of said anti-slipping device being transmitted through said cam plate to the plate 14 and heel 13.

Having thus described my invention, I claim:

1. A device of the character described comprising a plate arranged for attachment to the heel of a boot or shoe and provided with integral struck up flanges, an outer lift beneath said plate provided with a slot 70 extending therethrough from top to bottom and in which said flanges are received, an anti-slipping device movable in said slot into and out of operating position, and a cam slide guided between said flanges for operating said anti-slipping device.

2. The combination with a boot or shoe having a heel, of a resilient auxiliary lift secured to said heel, a guide plate embedded in said auxiliary lift between the top and bottom thereof, and an anti-slipping device guided by said plate and movable into and out of operative position.

3. A device of the character described comprising a plate arranged for attachment to the heel of a boot or shoe, a resilient outer lift beneath said plate provided with a slot extending therethrough from top to bottom, a plate embedded in said resilient lift between the top and bottom thereof, said last named plate being disconnected from said first named plate and having a slot registering with said first named slot, and an anti-slipping device movable in said slots into and out of operative position.

4. A boot or shoe provided with an anti-slipping device movable into and out of operative position and having a slot, and a leaf spring secured at one end to said boot or shoe and having its opposite end engaged in said slot.

5. The combination with a boot or shoe having a heel, of an outer lift secured to said heel and provided with an anti-slipping device movable into and out of operative position, said anti-slipping device having a slot, a plate interposed between said heel and outer lift, and a leaf spring secured at one end to said plate and having its opposite end engaged in said slot.

6. The combination with a boot or shoe, of a heel member provided with a slot extending therethrough from top to bottom, said member having a recessed upper face, an anti-slipping device movable in said slot 120 into and out of operative position and provided with a slot, and a leaf spring located in the recess in said heel member, said leaf spring being secured at one end to said boot or shoe and having its opposite end engaged in the slot in said anti-slipping device.

7. A boot or shoe provided with an anti-slipping device movable into and out of operative position, a cam slide for operating

said antislipping device, and a pivoted lever for operating said slide.

8. A boot or shoe provided with an antislipping device movable into and out of operative position and having a slot, a leaf spring secured at one end to said boot or shoe and having its opposite end engaged in said slot for moving said antislipping device out of operative position, a cam slide 10 for moving said antislipping device into operative position, and a pivoted lever for operating said slide.

9. The combination with a boot or shoe having a heel, of an outer lift secured to said heel and provided with an antislipping device movable into and out of operative position, a plate interposed between said heel and outer lift, a cam slide for operating said antislipping device, and a lever 20 pivoted to said plate for operating said slide.

10. The combination with a boot or shoe having a heel, of an outer lift secured to said heel and provided with an antislipping device movable into and out of operative position, said antislipping device having a slot, a plate interposed between said heel and outer lift, a leaf spring secured at one end to said plate and having its opposite 25 end engaged in said slot for moving said antislipping device out of operative position, a cam slide for moving said antislipping device into operative position, and a lever pivoted to said plate for operating 30 said slide.

11. The combination with a boot or shoe, of a heel member provided with a slot extending therethrough from top to bottom and with recesses in its upper face extending forwardly and backwardly respectively from said slot, an antislipping device mov-

able in said slot into and out of operative position, said antislipping device having a slot, a leaf spring secured at one end to said boot or shoe and having its opposite end 45 engaged in the slot in said antislipping device for moving said antislipping device out of operative position, said spring being located in one of said recesses, a cam slide for moving said antislipping device 50 into operative position, and a pivoted lever for operating said slide, said lever being located in the other of said recesses.

12. The combination with a boot or shoe having a heel, of an outer resilient lift secured to said heel and provided with a slot extending therethrough from top to bottom and with recesses in its upper face extending forwardly and backwardly respectively from said slot, a plate interposed between 55 said heel and lift, an antislipping device movable in said slot into and out of operative position, said antislipping device having a slot, a plate embedded in said outer lift by which said antislipping device is 60 guided, a leaf spring secured at one end to said first-named plate and having its opposite end engaged in the slot in said antislipping device for moving said antislipping device out of operative position, said 65 spring being located in one of said recesses, a cam slide for moving said antislipping device into operative position, and a lever pivoted to said first named plate for operating 70 said slide, said lever being located in the 75 other of said recesses.

In testimony whereof I affix my signature, in presence of two witnesses.

ALBERT C. RIGHOR.
